(No Model.)

J. BRISTOL.
CIGAR BUNCHING MACHINE.

No. 576,429.

Patented Feb. 2, 1897.

UNITED STATES PATENT OFFICE.

JACOB BRISTOL, OF DETROIT, MICHIGAN.

CIGAR-BUNCHING MACHINE.

SPECIFICATION forming part of Letters Patent No. 576,429, dated February 2, 1897.

Application filed February 25, 1896. Serial No. 580,684. (No model.)

To all whom it may concern:

Be it known that I, JACOB BRISTOL, a citizen of the United States, residing at Detroit, in the county of Wayne and State of Michigan, 5 have invented certain new and useful Improvements in Cigar-Bunching Machines, of which the following is a specification, reference being had therein to the accompanying drawings.

10 The invention consists in the peculiar construction, arrangement, and combination of parts, and especially in the means employed for reciprocating the bunching-table, more fully hereinafter described.

15 In the drawings, Figure 1 is a vertical longitudinal section through my cigar-bunching machine. Fig. 2 is a cross-section thereof on line x x , Fig. 1, with the apron omitted. Fig. 20 3 is a bottom plan view showing the arrangement of actuating connections for the table. Fig. 4 is a diagram of the bunching-table in the position where the pocket in the apron is just closing. Fig. 5 is a diagram of a modified form of actuating mechanism.

25 A is the main table. B are parallel slideways thereon, and C is the bunching-table, slidably secured on said slideways. The bunching-table is provided with a pocket-opening D, having the overhanging forward 30 end or shoulder a . At the rear end of the table C are the standards E. F is a roll journaled in these standards, to which the rear end of the apron G is attached, the other end being secured to the forward end of the bunching-table.

35 H are standards secured to the table A on opposite sides of the bunching-table, in which are journaled the concave roller I and bunching-roll J.

40 K are depending brackets or frames secured to the under side of the table A. L is a lever pivotally secured to the lower ends of these frames, having the upwardly-extending segment-arm L' and the foot-piece L² at its lower end.

45 M is a flexible strap or other connection attached at one end to the segment L' and, passing around the drum N, is secured at its opposite end to the forward end of the bunching-table. The drum N is journaled in the frames K and extends through an aperture N' in the table A.

O is another drum journaled to the rear of the frame K.

P is a flexible strap connected at one end 55 to the rear end of the table C and passing around the drum N in the opposite direction from the strap M and over the drum O is attached at its other end to a weight Q. I preferably use two straps P, arranged on opposite 60 sides of the strap M.

In practice the operator, taking his position in front of the table A, places the binder and filling on the apron G in the pocket-opening D and then by pressing his foot against the 65 foot-piece L² moves the lever L, rocking the segment-arm L', and drawing back the table on the slideways B. In this movement of the table the bunch is formed and rolled in contact with the roll J, the overhanging shoulder 70 a serving to contract the throat of the pocket in the apron and thereby close it without danger of throwing out the contents. The rolled bunch is finally deposited in the holder R at the forward end of the table. At the same 75 time the straps P have been drawn by the movement of the table raising the weight Q. Upon releasing the pressure of the foot upon the lever L the weight Q will draw back the parts to their original positions. 80

In Fig. 5 I show a modified form of actuating mechanism, in which flexible straps S are attached to the forward and rear ends of the bunching-table and extending oppositely are attached to the opposite ends of a segment-arm T, pivoted at T' and having the gear-segment T² on the opposite side of the pivots. 85

U is the operating foot-lever, pivoted at U' and having a gear-segment U², meshing with the segment T². By moving the lever U the 90 segment will be turned and the table reciprocated, the return movement being accomplished by a spring or other tension device.

It will be noticed that all the parts of my machine are attached to the table A, which 95 may be secured to an ordinary work-bench or in any suitable place.

What I claim as my invention is—

1. In a cigar-bunching machine, the combination with a horizontal table A having 100 horizontal guides thereon, of a bunching-table mounted on the guides, a single oscillating device projecting through the table A at a point midway the length of the guides, flexi-

ble straps or the like attached to the opposite ends of the bunching-table extending in opposite directions directly to and engaging respectively the opposite sides of the oscillating device, a lever having a segment at its end for moving the oscillating device, and means for restoring the oscillating device and table to their normal positions.

2. In a cigar-bunching machine, the combination with the table A of the horizontal slideways B thereon, the bunching-table C on said slideways, the brackets K depending from the under side of the table A, the rolls or drums N and O the former projecting above

the table A, and lever L journaled in the frame, the segment L' on the lever L, the flexible connections M and P secured respectively to the forward and rear ends of the table C and passing oppositely around the drum N, the former being secured to the segment L' ^{2c} and the latter passing over the roll O, and the weight Q attached to the connection P.

In testimony whereof I affix my signature in presence of two witnesses.

JACOB BRISTOL.

Witnesses:

M. B. O'DOGHERTY,
O. F. BARTHEL.
